DESIGN FOR A SHOE OR SIMILAR ARTICLE

Salvatore Ferragamo, Florence, Italy

Application January 20, 1938, Serial No. 74,426

Term of patent 3½ years

To all whom it may concern:

Be it known that I, Salvatore Ferragamo, a citizen of the United States of America, residing in Florence, Italy, have invented a new, original, and ornamental Design for a Shoe or Similar Article, of which the following is a specification, reference being had to the accompanying drawing, forming part thereof.

I claim:

The ornamental design for a shoe or similar article, substantially as shown.

SALVATORE FERRAGAMO.
